(57) **CLAIM**

The ornamental design for dental light, as shown and described.

DESCRIPTION

FIG. 1 is a front perspective view of a dental light incorporating the design of my new invention;

FIG. 2 is a rear perspective view thereof;

FIG. 3 is a front elevational view thereof;

FIG. 4 is a right side elevational view thereof;

FIG. 5 is a rear elevational view thereof;

FIG. 6 is a top plan view thereof; and,

FIG. 7 is a bottom plan view thereof.

The features of the dental light shown in phantom lines are not elements of the design of my new invention.
